CLAIM

The ornamental design for an LED light as shown and described.

DESCRIPTION

FIG. 1 is a perspective view of an LED light showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the circled area 9 of FIG. 1;

FIG. 10 is an enlarged view of the circled area 10 of FIG. 1;

FIG. 11 is an enlarged view of the circled area 11 of FIG. 2;

FIG. 12 is an enlarged view of the circled area 12 of FIG. 2;

FIG. 13 is an enlarged view of the circled area 13 of FIG. 2;

and,

FIG. 14 is an enlarged view of the circled area 14 of FIG. 2.

The dash-dash broken lines illustrate portions of the LED light. The dot-dash broken lines represent the boundaries of the enlarged views. The broken lines form no part of the claimed design.

1 Claim, 14 Drawing Sheets
